UNITED STATES PATENT OFFICE.

ALBERT F. BREITENSTEIN AND ERWALD A. BARTEIT, OF NEW HAVEN, CONNECTICUT, ASSIGNORS TO THE GEOMETRIC TOOL CO., OF NEW HAVEN, CONNECTICUT, A CORPORATION.

NONROTARY SELF-OPENING DIE HEAD.

Application filed January 26, 1926. Serial No. 83,780.

Fig. 1 is a view in side elevation of our improved die-head, shown as closed.

Fig. 2 is a view thereof in front elevation.

Fig. 3 is a view thereof in vertical, central, 5 longitudinal section, as closed.

Fig. 4 is a similar view, with the parts thereof in the positions due to them when the fixture is about to open.

Fig. 5 is a corresponding view, as open.

10 Fig. 6 is a broken, longitudinal, sectional view on the line 6—6 of Fig. 2.

Fig. 7 is a corresponding view on the line 7—7 of Fig. 2.

15 Fig. 8 is a corresponding view on the line 8—8 of Fig. 2.

Fig. 9 is a detached view in front elevation of the locking-member of the fixture.

Fig. 10 is an edge view thereof.

20 Fig. 11 is a detached view, in front elevation, of the operating-member of the fixture.

Fig. 12 is a view thereof in side elevation, partly in section.

Fig. 13 is a detached view, in front elevation, of the adjusting-ring of the fixture.

25 Fig. 14 is a view thereof in side elevation, partly in section.

Fig. 15 is a detached view, in side elevation, of the chaser-carrying member of the fixture.

30 Fig. 16 is a view thereof in rear elevation.

Fig. 17 is a detached view, in front elevation, of the mounting-member of the fixture.

Fig. 18 is a view thereof in side elevation, with its shank broken away.

35 Our invention relates to an improvement in non-rotary, self-opening die-heads, the object being to produce a fixture of the character described, constructed with particular reference to ruggedness and durability in use, simplicity of operation, convenience of adjustment, positiveness of action, and accuracy of performance.

40 With these ends in view, our invention consists in a non-rotary, self-opening die-head characterized by having a mounting-member, a chaser-carrying member, chasers mounted therein, an operating-member, and a locking-member located between the chaser-carrying member and the operating-member, the said operating- and chaser-carrying members having relative, rectilinear movement with respect to each other and with respect to the mounting-member, and the said locking-member being releasable 45 for unlocking the die-head by the forward

draft imposed upon the chasers by the work.

Our invention further consists in a non-rotary, self-opening die-head characterized as above, and having certain other details of construction as will be pointed out in the 50 claims.

In carrying out our invention, as herein shown, we employ a mounting-member 20, a chaser-carrying member 21, an operating-member 22, and a locking-member 23. The 55 said mounting-member 20 has a hollow shank 24, by means of which the fixture is mounted in a turret 25, or the equivalent feature of any machine suitable for threading operations.

At its forward end, the said mounting-member 20 is provided with a concentric bore 26 for the sliding reception of the hollow shank 27 of the chaser-carrying member 21, the forward face of which is provided 70 with four radially-arranged slots 28 receiving radially-movable chasers 29 having their inner ends formed with cutting-teeth 30, and their outer ends provided with bevels 31 for co-action with beveled notches 32 located within the forward end of the sleeve-like operating-member 22, which is slidably mounted upon the forward end of the chaser-carrying member 21.

75 Each of the chasers 29 is provided, near its outer end, with a rearwardly-extending pin 33, engaged by a plunger 34 normally urged outward by a spring 35, the said plunger and spring being located in a radial bore 36 formed in the chaser-carrying member 21, and intercommunicating with the radial slots 28 aforesaid.

80 At its rear end, the sleeve-like operating-member 22 is internally-threaded for the reception of the externally-threaded, tubular, forward end of an adjusting-ring 37, virtually forming a part of the said operating-member, and sliding upon the mounting-member 20, the flanged rear end of the said ring being provided with radial wrench-sockets 38 for the application of an ordinary spanner wrench, by means of which the ring is turned inward or outward as desired, with respect to the operating-member 22, so as to change the position of the beveled notches 32 therein, with respect to the locking-member 23, whereby the diameter of the threads cut by the chasers may be varied.

85 The forward face of the flanged rear end of the adjusting-ring 37 is provided with 100 105 110

an annular series of circular, shallow seats or depressions 39, with any one of which a friction-plunger 40 is normally engaged for preventing the accidental rotation, by 5 the jarring of the fixture when in use, of the ring 37 with respect to the operating-member 22, which is formed with a bore 41 for the reception of the said plunger 40, and also for the reception of the spring 42, 10 and by means of which the same is operated.

For preventing the relative rotation of the chaser-carrier 21 and the mounting-member 20, without interfering with their relative, rectilinear movement, the mounting-member 20 is formed at its forward end with two oppositely-located, integral coupling-lugs 43, embracing the straight sides of a coupling-boss 44 formed between the main body of the chaser-carrying member 21 15 and the shank 27 thereof.

For preventing the relative rotation of the chaser-carrying member 21 and the operating-member 22 without interfering with their relative, rectilinear movement, we employ 20 two locking-pins 45, driven into and projecting forwardly from an annular bearing-rib 46 formed within the operating-member 22 and entering sockets 47 in the chaser-carrier, as shown in Fig. 7.

30 To provide for the rectilinear, rearward movement of the operating-member 22, with respect to the chaser-carrying member 21, for the purpose of permitting the chasers to move into their open positions, under the 35 normal urge of their springs 35, we employ springs 48, located diametrically opposite each other in registered bores 49 and 50, respectively formed in the said members 21 and 22, as shown in Fig. 8. Each spring 48 encircles a guide-pin 51 mounted in the chaser-carrier 21 and extending rearwardly therefrom, through its bore 49, and partly into the corresponding bore 50 in the operating-member 22.

45 For locking the operating-member in its closed or thread-cutting position, as shown in Fig. 3, against the counter-urge of the springs 48, just described, we employ the segmental locking-member 23, before mentioned, the same being located in a forwardly-inclined, substantially semi-circumferential slot 52, formed in the mounting-member 20, as clearly shown in Figs. 17 and 18.

50 This locking-member is formed, at its rear end, with a segmental, external locking-rib 53, the forward edge of which co-acts with the forward wall of a shallow, circumferential, internal locking-groove 54 formed in the adjusting-ring 37, as shown in Figs. 13 and 14. Near its forward end, the said locking-member is formed with a segmental, internal coupling-rib 55, entering a corresponding coupling-groove 56 (Figs. 15 and 16) in the shank 27 of the chaser-carrying member, whereby the said locking-member

participates in the rectilinear movement of the chaser-carrying member.

In order to disengage the forward edge of its locking-rib 53 aforesaid from the forward wall of the internal groove 54 aforesaid, the locking-member is concurrently moved inwardly, as well as forwardly, by its provision with a bevel 57, forming its forward face and riding upon the forward wall 58 of the inclined slot 52 in the mounting-member 20. For re-locking the fixture with the chasers 29 in their cutting positions, the locking-member 23 is concurrently moved rearward and outward for the reentrance of its locking-rib 53 into the groove 54. For this purpose, the said member is formed with a beveled, rear face 59, which coacts with the rear wall 60 of the said inclined slot 52.

55 The rearward and outward movement of the locking-member, for re-setting the fixture, is effected by means of a re-setting handle 61 rocking on a pin 62 in a clearance-passage 63 in the operating-member 22, the spherically-contoured inner end 64 of the said lever passing through a clearance-passage 65 in the mounting-member 20, into the socket 66 in the shank 27 of the chaser-carrying member 21.

60 For limiting the chaser-opening movement of the operating-member 22, we employ a plunger 67 mounted in a bushing 68 screwed into the operating-member 22, and at its inner end entering an elongated recess 69 formed in the periphery of the mounting-member 20, and having, at its rear end, a hardened abutment-pin 70, against which the inner end of the plunger 67 impinges, the plunger being normally held in the recess 69 by a spring 71 located within the bushing 68. For the retraction of the plunger from the recess 69 to permit the operating-member to move into its chaser-removal-and-replacement position, it is provided with a knurled button 72.

65 Under the above described construction and arrangement of parts, it will be seen that while the mounting-member, the chaser-carrying member and the operating-member are held against relative rotary movement, the chaser-carrying and chaser-operating members have relative, rectilinear movement with respect to each other, as well as with respect to the mounting-member, this being one of the characteristic features of our improved, non-rotary, self-opening die-head.

70 In the use of our improved die-head, the work represented by broken lines 73 is rotated in the usual manner, while the non-rotary die-head is bodily moved toward the work, on the axial line thereof, by the turret 25, or by whatever other fixture the die-head may be mounted in, the die-head being, at this time, re-set and locked, with its chasers in their cutting positions. The cutting edges of the chasers now engaged with the

work and begin the cutting operation, during which, as it will be understood, the die-head is manually urged toward the work, with more or less pressure, as required. When 5 the desired length of thread has been cut in the work, the forward movement of the die-head is stopped, either by an abutment on the machine or by the deliberate act of the operator. The parts of the die-head will 10 now be in the positions in which they are shown in Fig. 3.

The work continuing to rotate, on account of being threaded into the chasers, will pull the chaser-carrying member toward it in a 15 rectilinear path, away from the mounting-member, for a slight distance. At the same time, the operating-member will be correspondingly moved in a rectilinear path, due to the fact that at this time it is positively 20 coupled with the chaser-carrying member by the locking-member 23, which extends between the two members. Concurrently with this rectilinear movement of the said two members, the locking-member is being positively 25 moved bodily inward, as well as forward, so that, at the termination of the concurrent, rectilinear movement of the two members, the locking-member has been so far moved bodily inward that the forward 30 edge of its locking-rib 53 will be disengaged from the forward wall of the shallow groove 54 in the operating-member, as shown in Fig. 4. At the instant the said disengagement takes place, the operating-springs 48 35 assert themselves to effect the rearward, rectilinear movement of the operating-member, independently of the chaser-carrying member and the mounting-member, until the plunger 67 strikes the hardened stop-pin 70, 40 whereby the chaser-springs 35 are permitted to move the chasers 29 radially outward and so release them from engagement with the work 73. The parts will now be in the position shown in Fig. 5, with the re-setting 45 handle 61 rearwardly inclined.

The die-head being now disengaged from the work, it is bodily retired, and a new piece of work is put in place. The die-head is now re-set by swinging the re-setting 50 handle from rear to front, effecting the rectilinear forward movement of the operating-sleeve, independently of the chaser-carrying member and of the mounting-member, whereby the forward wall of the 55 annular groove 54 is moved forward and brought into line with the forward edge of the locking-rib 53 of the locking-member 23. This phase of the re-setting operation moves the parts from the position shown in Fig. 5 60 to the position shown in Fig. 4.

Now, inasmuch as the shank 27 of the chaser-carrying member 21 provides one of the two fulcra of the re-setting lever 61, the chaser-carrying member will be urged rear- 65 ward in a rectilinear path, at the same time

the operating-member is being moved forward in a rectilinear path by the handle. Therefore, at the instant the forward edge of the locking-rib 53 registers with the forward wall of the shallow groove 54, the 70 chaser-carrier will move slightly rearward in a rectilinear path, whereby the locking-member will have its rear face 59 forced against the rear wall 60 of the slot 52, with the effect of positively moving the locking-member outward, as well as rearward, so as to cause its locking-rib 53 to enter the slot 54. In this last phase, the locking-member moves from the position shown in Fig. 4 to the position shown in Fig. 3. 75

The die-head now having been re-set, is advanced as before to the work, and the cycle of operations above detailed repeated.

We claim:

1. A die-head having a mounting-member provided with a slot inclined with respect to its axis and having parallel walls, a chaser-carrying member, chasers mounted therein, a chaser-operating member, and a locking-member therefor located in the said inclined slot and having movement therein in the inclined plane thereof, said chaser-operating and chaser-carrying members having relative, rectilinear movement with respect to each other and with respect to the said mounting-member, and the said locking-member being moved for unlocking the die-head by the forward draft imposed upon the chaser-carrying member by the work and moved for locking the die-head by the reverse movement of the said chaser-carrying member. 95

2. A non-rotary, self-opening die-head, having a mounting-member provided with a slot inclined with respect to its axis and having parallel walls, a chaser-carrying member, chasers mounted therein, a chaser-operating member, and a locking-member located in the said inclined slot and having movement therein in the inclined plane thereof, the said chaser-carrying and chaser-operating members having relative rectilinear movement with respect to each other and with respect to the said mounting-member, and the locking-member being interposed between the chaser-carrying and chaser-operating members, so as to be moved for unlocking the die-head by the forward draft imposed upon the chaser-carrying member by the work and moved for locking the die-head by the reverse movement of the said chaser-carrying member. 115

3. A non-rotary, self-opening die-head, having a mounting-member provided with a slot inclined with respect to its axis, a chaser-carrying member slidably mounted in the mounting-member, a chaser-operating member slidably mounted upon the said chaser-carrying member, and a locking-member for the said chaser-operating mem- 125
130

- ber, having movement in the said inclined slot in the inclined plane thereof and positioned between the said chaser-carrying member and the chaser-operating member, 5 the said chaser-carrying and chaser-operating members having relative, rectilinear movement with respect to each other and with respect to the mounting-member, and the said locking-member being moved for 10 unlocking the die-head by the forward draft imposed upon the chasers by the work.
4. A non-rotary, self-opening die-head, having a mounting-member provided with a slot inclined with respect to its axis, a 15 chaser-carrying member, chasers mounted therein, a chaser-operating member, an adjusting-member carried by the chaser-operating member at the rear end thereof, and a locking-member for the said chaser-operating member, located in the said inclined slot and positioned between the chaser-carrying member and the chaser-operating member and having bodily movement 20 in the said inclined slot in the plane thereof, the said chaser-carrying and chaser-operating members having relative, rectilinear movement with respect to each other and with respect to the said mounting-member, and the said locking-member being moved for 25 unlocking the die-head by the forward draft imposed upon the chasers by the work.
5. A non-rotary, self-opening die-head, having a mounting-member provided with a slot inclined with respect to its axis, a 30 chaser-carrying member carried thereby, chasers mounted therein, a chaser-operating member mounted upon the said mounting-member, an adjusting-ring carried by the chaser-operating member at the rear end thereof, and riding upon the said mounting-member, and a locking-member for the said chaser-operating member, located in the 35 said inclined slot, positioned between the said chaser-carrying and chaser-operating members, and bodily moved in the inclined plane of the said slot by the relative movement between the said mounting-member and the said chaser-carrying member, the 40 said chaser-carrying and operating-members having relative, rectilinear movement with respect to each other and with respect to the mounting-member, and the said locking-member being moved for 45 unlocking the die-head as the result of the forward draft imposed upon the chasers by the work.
6. A non-rotary, self-opening die-head, having a mounting-member provided with a slot inclined with respect to its axis, a 50 chaser-carrying member carried by the said mounting-member and sliding therein, chasers mounted in the said chaser-carrying member, a chaser-operating member, and a locking-member therefor, located in the 55 said inclined slot, having bodily movement 60

therein and extending between the said chaser-carrying and chaser-operating members, and having relative, rectilinear movement with respect to each other and with respect to the said mounting-member, and the said locking-member being moved for 70 unlocking the die-head as the result of the forward draft imposed upon the chasers by the work.

7. A non-rotary, self-opening die-head, 75 having a mounting-member, a chaser-carrying member mounted therein and provided with a peripheral coupling-groove, chasers carried by the said chaser-carrying member, a chaser-operating member sliding upon the said mounting-member and having a locking-groove, and a locking-member for the said chaser-operating member, extending between the chaser-carrying and chaser-operating members, and having an internal 80 rib co-acting with the said coupling-groove in the chaser-carrying member, and an external rib co-acting with the locking-groove in the said chaser-operating member, the said chaser-carrying and operating members having relative, rectilinear movement with respect to each other and with respect to the mounting-member, and the said locking-member being disengaged from one of the members with which it engages as the result of the outward draft imposed upon the 85 chasers by the work.

8. A non-rotary, self-opening die-head, having a mounting-member provided with a slot inclined with respect to its axis and having parallel walls, a chaser-carrying member, chasers mounted therein, a chaser-operating member, a locking-member for the said chaser-operating member, located in the said slot and positioned between the said chaser-carrying member and chaser-operating member, which latter have relative, rectilinear movement with respect to each other and with respect to the mounting-member, and the said locking-member having bodily movement in the said inclined slot in a plane inclined with respect to the axis of the die-head for unlocking the die-head as the result of the forward draft imposed upon the chaser-operating member by the work, and a re-setting lever extending between the operating-member and the chaser-carrying member for effecting their relative, reverse rectilinear movement, whereby the locking-member is moved into position for locking the chasers in their closed positions.

9. A non-rotary, self-opening die-head, having a mounting-member provided with an inclined slot having outer and inner walls, a chaser-carrying member mounted in the said mounting-member, chasers mounted in the said chaser-carrying member, a chaser-operating member, and a locking-member for the said chaser-oper- 125 130 135

- ating member, located in the said slot, and extending between the said chaser-carrying and chaser-operating members, the said chaser-carrying and chaser-operating members having relative, rectilinear movement with respect to each other and with respect to the mounting-member, and the said locking-member being bodily moved forwardly and inwardly, and rearwardly 5 and outwardly, by the outer and inner walls of the inclined slot in which it is located, for locking and unlocking the fixture.
10. A non-rotary, self-opening die-head, having a mounting-member provided with a slot inclined with respect to its axis, a chaser-carrying member, chasers mounted therein, a chaser-operating member, a chaser-adjusting member carried thereby at the rear end thereof and formed with a 15 locking-abutment, and a locking-member for the chaser-operating member, located in the said inclined slot and having bodily movement therein in the plane thereof and co-acting with the said abutment of the adjusting-member for maintaining the chasers 20 in their cutting positions, and the said chaser-carrying and chaser-operating members having relative, rectilinear movement with respect to each other and with respect 25 to the said mounting-member, and the said locking-member being moved for unlocking the die-head by the forward draft imposed upon the chasers by the work.
11. A non-rotary, self-opening die-head, 30 having a mounting-member provided with a substantially semi-circumferential slot extending between its inner and outer peripheries and inclined with respect to its axis and having parallel walls, a chaser- 35 carrying member, chasers mounted therein, a chaser-operating member, and a segmental locking-member therefor located in the said inclined slot and having bodily movement therein in the inclined plane thereof, and the 40 said chaser-operating and chaser-carrying members having relative, rectilinear movement with respect to each other and with respect to the said locking-member, and the 45
- said locking-member being moved for unlocking the die-head by the forward draft imposed upon the chaser-carrying member by the work, and means for manually effecting the reverse relative movement of the chaser-carrying and chaser-operating members, whereby the said locking-member is moved in the opposite direction for locking the chasers in their closed positions. 50
12. A non-rotary, self-opening die-head, having a mounting-member provided with a slot inclined with respect to its axis, a chaser-carrying member provided with a peripheral coupling-groove, chasers carried by the said chaser-carrying member, a chaser-operating member provided with a locking-abutment, and a segmental locking-member 55 located in the said inclined slot and having bodily movement therein and provided with a segmental coupling-rib entering the peripheral coupling-groove in the chaser-carrying member, and with a segmental locking-rib co-acting with the locking-abutment 60 aforesaid of the chaser-operating member. 70
13. A non-rotary, self-opening die-head having a mounting-member provided with a tubular shank and with a slot inclined with respect to its axis, a chaser-carrying member having a tubular shank entering the said tubular shank of the mounting-member, chasers mounted in the said chaser-carrying member, a chaser-operating sleeve 75 sliding upon the said mounting-member, and a segmental locking-member located in the said inclined slot and having bodily movement therein in the inclined plane thereof and interposed between the said chaser-carrying and operating-members and coupled with the chaser-carrying member and having intermittent engagement, according to 80 the position thereof, with the chaser-operating member for holding the same in the 85 chaser-closing position. 90

In testimony whereof, we have signed this specification.

ALBERT F. BREITENSTEIN.
ERWALD A. BARTEIT.
